UNITED STATES PATENT OFFICE.

AUGUST WOLFF, OF NEW YORK, N. Y.

WINDOW.

976,534.

Specification of Letters Patent. Patented Nov. 22, 1910.

Application filed September 15, 1909. Serial No. 517,767.

To all whom it may concern:

Be it known that I, AUGUST WOLFF, a citizen of the United States of America, residing in New York, in the borough of the Bronx, county and State of New York, have invented certain new and useful Improvements in Windows, of which the following is a specification.

This invention relates to certain improvements in windows in which, instead of glass panes, a sheet or sheets of waterproof transparent and flexible material, such as celluloid are used, said sheets being adapted to be wound up on suitable rollers in such a manner that the window can be partly or entirely opened so as to permit of partial or full ventilation, and in which the sheets are held in tightly clamped and stretched position whether in partly or entirely closed position.

The invention relates further to means for clamping the sheets in closed or partly open position for use, and means for winding up or unwinding the sheets, according as the window is to be opened or closed.

In the accompanying drawings, Figure 1 represents a front-elevation of my improved window, showing it in partly open position, Fig. 2 is a vertical transverse section of the same on line 2, 2, Fig. 1, Fig. 3 is a horizontal section, on line 3, 3, Fig. 1, drawn on a larger scale, and showing the mechanism for opening or closing the window, Fig. 4 is a detail side-elevation of the mechanism for raising or lowering the transparent sheet of the window, Fig. 5 is a perspective view of the means for tightly holding the transparent window-sheet in position, Fig. 6 is a vertical transverse section of my improved window with an upper and lower window-sheet and the mechanism for moving the upper and lower half of the window-sheet separately from each other into a top and sill box, and Fig. 7 is a vertical transverse section of a window with a double sheet constructed on the same lines as the single-sheet window.

Similar letters of reference indicate corresponding parts throughout the several views.

Referring to the drawings, a represents the window-casing, a^1 the upper or top boxes, and a^2 the lower or sill box of my improved window. The window, instead of being two sashes and glass panes, is made of one continuous sheet b of waterproof transparent and perfectly clear celluloid, or

equivalent material, of sufficient size, which is guided at both sides in longitudinal slits of the jambs of the window-casing and extended into side-boxes a^3 . The opposite side-edges of the transparent sheet b are provided with perforations b^1 which are engaged by studs or projections b^2 arranged on endless bands b^3 that are stretched over driving and guiding rollers b^5 , b^6 , located respectively in the sill and top box of the casing, as shown in Figs. 1 and 2. A second pair of endless bands b^4 is arranged adjacent to the endless bands b^3 and stretched over driving and guiding rollers b^7 , b^8 arranged adjacent to the rollers b^5 , b^6 , the bands b^4 being provided with perforations registering with the studs or projections b^2 of the endless driving bands b^3 , so that when the projections b^2 enter the perforations of the window-sheet b they enter also the perforations of the bands b^4 and take the transparent window-sheet along for opening or closing the window-casing. On the shafts of the lower rollers b^5 , b^7 are arranged gear-wheels g , g^1 which mesh with each other, said shafts being supported in bearings in the jambs of the window-casing and metallic supporting frames or keepers b^9 , while the shafts of the guide-rollers b^6 , b^8 are likewise supported in bearings in the jambs and metallic frames or keepers b^{10} , as shown in Figs. 3 and 4. The gear-wheels g of the bands b^3 are also placed in mesh with gear-wheels g^2 , which again engage gear-wheels g^3 on the shaft of a winding-up roller g^4 to which the lower end of the window-sheet b is attached so as to be wound up on the roller or unwound from the same when the gear-wheels g are turned in one or the opposite direction. The shafts of the gear-wheels g^3 and winding-up roller g^4 turn in bearings in the side-walls of the sill-box and a suitable frame or keeper g^5 , as shown in Fig. 4. The winding-up roller g^4 is located in the sill-box a^2 which is closed by a pivoted inner sill d , and an outer stationary sill d^1 , the latter being slightly inclined for shedding the rain-water. Between the adjacent edges of the inner and outer sills the window-sheet b is conducted when raising or lowering it by the action of the roller g^4 and operating bands. When the inner pivoted sill d is tilted, access is given to the gearing of the endless bands b^3 , b^4 and the roller g^4 in the sill-box. The window-sheet b is provided at its upper edge with an angular metallic

strip e , which is attached thereto by rivets or otherwise, and which abuts against the top of the window-casing when the window is closed. When the sheet is to be partly or 5 entirely opened, the angular strip e is engaged by the hook-shaped end of a hand-rod and lowered or raised as required. The studs of the endless bands b^3 engage the perforated edges of the sheet by the action of 10 the gear-wheels and wind the lower part of the sheet on the winding-up roller. When the angular strip e is raised, the train of gear-wheels is operated in the opposite direction, then the sheet is unwound from the 15 roller, and the angular strip moved up against the top-part of the window-casing. In Figs. 1 and 2, the window is shown as partly open, but it can be entirely opened by winding up the sheet on the winding-up 20 roller until the edge-strip e arrives at and abuts against the sill.

Alongside of the longitudinal slits in the jambs of the window-casing is arranged an outer stationary angular strip f , which is 25 attached in fixed position to the jamb, and an inner movable angular strip f^1 , which is located adjacent to the opposite edge of the slits in the jambs, as shown in Fig. 3. The adjustable strip f^1 is provided with horizontal slots f^2 at its upper and lower ends, and guided on headed pins f^3 in the same. By means of a suitable lever f^4 , which is pivoted at its upper end to the movable 30 guide-strip f^1 and attached by a pin f^5 at its middle portion through a slot f^6 in the movable strip f^1 with the jamb, the latter can be pressed firmly against the edge of the sheet so as to hold it tightly in any desired 35 position. The stationary strip f and the movable strip f^1 are provided with grooves in their adjacent faces in which beaded strips f^7 , f^8 are inserted so as to tightly clamp the sheet b and prevent any ingress 40 of water to the side-boxes of the casing. 45 The water running down on the outer surface of the window-sheet b is collected in the sill-box and conducted over the inclined bottom of the same to the outside. When it is desired to raise or lower the window- 50 sheet, the movable strips f^1 have to be released from the edges of the sheet so that it can then be freely adjusted. When the proper adjustment is made, the strips are tightly clamped to the window-sheet for 55 holding it rigidly in position.

In some cases, especially for windows of larger size, it is preferable to make the window-sheets in two sections, an upper and a lower one, corresponding to the upper and 60 lower sashes of the ordinary window. This is shown in Figs. 5 and 6. In this case, the upper window-sheet b^x is provided with an angular meeting strip e^1 at its lower edge, in the same manner as the upper edge of the 65 lower sheet. Two sets of raising and lower-

ing mechanisms are then required, one being located in the sill-box and the other arranged in the top-box of the window-casing. Both sheets b and b^x are operated by the hand-rod, the hook-shaped end of which engages the angular strips e or e^1 . The clamping mechanisms for holding the upper and lower window-sheets are of the same construction as the clamping mechanism for the single window-sheet shown in Figs. 1 75 to 4, while the guide-rollers for the endless operating bands are located adjacent to each other at the middle portion of the window-casing.

For country houses and sections of the 80 country having cold winters, double windows can be provided. Fig. 7 shows a double window with upper and lower window-sheets. In this case four adjusting mechanisms are required, two in the sill-box and 85 two in the top-box. An air-space is formed between the window-sheets, while the clamping mechanisms for the edges of the sheets are constructed in the same manner as in single-sheet windows.

The advantages of my improved window with waterproof celluloid sheets are that the 90 objectionable breakage of the glass panes is avoided, that the windows can be opened entirely so as to get the full ventilating effect of the entire window-opening without any inwardly-projecting parts or wings, and that no rain can enter into the rooms. Whatever rain or moisture is collected on the outside of the window-panes is 95 conducted into the sill-box and conducted off to the outside. Owing to the firm clamping of the edges of the sheets, they are held firmly in stretched position so as to resist the strain caused by wind pressure, while 100 the windows can be opened and closed in a quick and easy manner and clamped in partly open or closed position.

Having thus described my invention, I 110 claim as new and desire to secure by Letters Patent:

1. The combination, with a window casing having side boxes and longitudinal guide-slits therein, of a sheet of flexible material having its edges guided in said slits and projecting into said boxes, and means located within said boxes and grasping said edges at a plurality of points for moving said sheet into closed or open position.

2. The combination, with a window casing having side boxes and longitudinal slits opening into said boxes, of a sheet of flexible material having its side edges projecting through said slits into said boxes, endless bands located in the side boxes and provided with means for engaging the sheet moving it into closed or open position, and means for moving the bands.

3. The combination, with a window casing having side boxes provided with longi- 130

tudinal guide slits opening into the boxes, of a sheet of flexible material having its edges projecting through said slits and into said boxes, endless bands located in said 5 boxes and provided with means for engaging said edges, guide-rollers for supporting said bands and a winding up roller for said sheet.

4. The combination, with a window casing having side boxes provided with longitudinal guide slits opening into the boxes, of a sheet of flexible material having its edges projecting through said slits and into said boxes, endless bands located in said 10 boxes and provided with means for engaging said edges, guide-rollers for supporting said bands, a winding-up roller for said sheet, and means for moving said guide-rollers and said winding-up roller in unison.

20 5. The combination of a window-casing provided with side-boxes having longitudinal guide-slits opening therein, sheets of transparent waterproof material guided in the upper and lower portions of said slits 25 and projecting into said boxes, transverse meeting strips at the adjacent ends of the upper and lower sheets, and means in said boxes for engaging and winding up or unwinding said sheets for opening or closing 30 the windows.

6. The combination of a window-casing provided with side-boxes having longitudinal guide-slits opening into said boxes, a sheet of waterproof transparent material 35 projecting through said slits into said boxes and having perforations in the edges of the same, a pair of endless bands in said boxes and provided with studs or projections for engaging the perforated edges of 40 said sheet, a second pair of endless bands at the opposite side of the sheet having perforations in their edges registering with the studs and perforations of the sheet, rollers for guiding said endless bands, a winding-up roller for the sheet, and a train of 45 gear-wheels for operating the endless bands and turning the winding-up roller for winding and unwinding the sheet.

7. The combination of a window-casing 50 provided with side-boxes having longitudinal guide-slits opening therein, a waterproof transparent and flexible sheet pro-

jecting through said slits into said boxes, means in said boxes for engaging and winding up or unwinding the edge of the sheet 55 for opening or closing the window, stationary clamping strips alongside of the slits at the outside of the sheet, movable clamping strips at the inner edges of the slits and inside of the sheet, said stationary and 60 movable clamping strips having beaded elastic strips at their edges, and means for moving the inner clamping strips toward the outer strips for clamping the edges of the sheet when in partly or entirely closed 65 position.

8. The combination of a window-casing having top, side and sill boxes, and jambs provided with longitudinal guide-slits, sheets of waterproof transparent and flexible 70 material guided in said slits, endless bands located in the side-boxes and provided with engaging means for moving the sheet into closed or open position, guide-rollers located in the side-boxes, winding- 75 up rollers for the sheets located in the sill and top boxes, and means for winding or unwinding the endless bands and sheets and turning the winding-up rollers for unwinding or winding up the sheets into closed or 80 open position.

9. The combination of a window-casing having top, side and sill boxes, and jambs with longitudinal slits, waterproof transparent and flexible sheets guided in said 85 slits, two pairs of endless bands at opposite sides of said sheets provided with means for engaging the same for raising or lowering the sheets into closed or open position, guide-rollers for said endless bands located 90 in the side-boxes, winding-up rollers for the window-sheets located in the sill and top boxes, and gear-wheels for turning the winding-up rollers for unwinding or winding up the sheets for closing or opening the 95 window.

In testimony, that I claim the foregoing as my invention, I have signed my name in presence of two subscribing witnesses.

AUGUST WOLFF.
